UNITED STATES PATENT OFFICE

154,266

DESIGN FOR A PERFUME DISPLAY BOX

Elizabeth N. Graham, New York, N. Y.

Application November 20, 1947, Serial No. 142,673

Term of patent 14 years

(Cl. D80—5)

To all whom it may concern:

Be it known that I, Elizabeth N. Graham, a citizen of the United States of America, residing in New York city, county of New York, and State of New York, have invented a new, original, and ornamental Design for a Perfume Display Box, of which the following is a specification, reference being had to the accompanying drawing, forming part thereof, wherein,

The rear of the perfume display box is identical in appearance to the front shown, except for the omission of the ornamental figurine.

I claim:

The ornamental design for a perfume display box, substantially as shown and described.

ELIZABETH N. GRAHAM.
